CAN PUNCH

Bernard E. Dougherty, Seattle, Wash.

Application February 6, 1934, Serial No. 710,037

11 Claims. (Cl. 164—120)

This invention relates to a can punch and more particularly to a manually operable can punch adapted for use on flanged cans, and more especially soldered cans wherein the flange is little 5 or no more than the thickness of the metal.

From time to time there have appeared can punches involving clamps which embrace the can to be punctured. Such devices are cumbersome and are not conveniently adapted for use on 10 various size cans. It is desirable that can punches make an opening adjacent the edge of the can whereby the whole of the contents may conveniently be poured from the can. The types of punches depending upon embracing the can 15 with a clamp are not only difficult of manipulation and bulky to store, but are almost without exception limited to spaced perforations which, on larger sized cans, lie inwardly of the edge and render difficult the emptying of the can inasmuch 20 as inverting the can to present the opening to the last of the contained liquid results in air locking. My improved can punch is operable with equal facility and efficiency upon cans of any size, always making the perforation adjacent 25 the edge of the can of any size; the perforation can be made adjacent the edge of the can irrespective of its size, resulting in utmost efficiency in providing an air relief hole and an emptying 30 hole diametrically opposed and adjacent the edge of any size can.

Other can punches have been devised which combine handles for manipulating the can after perforation. It is not my purpose to provide a handle to serve to hold a can. My improved 35 can punch is operable manually and conveniently with the same general motions as employed with a cap remover for crown seals. It is readily applied to a can, taking a firm and tenacious grip thereon irrespective of the size of the flange on 40 the can and readily perforating the same and shearing the metal if desired back to the edge of the can forming a clean opening without interior obstruction at the most efficient point of the can for emptying the same. My can punch 45 is particularly well suited for condensed milk cans which, by common acceptance, are soldered cans having a flange no thicker than the material of the can. Can punches as ordinarily available fail to engage such a small flange with sufficient 50 tenacity to resist the reaction forces developed in puncturing the can. My can punch is so constituted that no manipulation other than the familiar operation of a bottle cap remover is required in perforating a can even with so slight 55 a flange.

In the accompanying drawing illustrating certain preferred embodiments of my invention:

Figure 1 illustrates a can punch embodying my invention, as applied to a can being punctured;

Figure 2 illustrates another form of can punch showing my invention applied to a can being 5 perforated; and

Figure 3 illustrates another form of can punch similar in some respects to that illustrated in 10 Figure 1.

Referring to Figure 1, there is shown a can punch comprising a puncture point 2 on a member 3 pivoted on a fulcrum 4 and rotatable about such fulcrum by a handle 5. The fulcrum is part of a bracket 6 having a tooth 7 for engagement 15 with the flange 8 of the can 9, and a foot 10 for engagement with the top 11 of the can. The punch is shown in dotted lines in initial position prior to perforation of the can and in solid lines in position shortly before completion of the puncturing operation.

The bracket 6 comprises a generally flat portion 12 having an opening 13 therein through which the member 3 is free to operate. The fulcrum 4, in the embodiment shown in Figure 1, 25 is formed by ears 14 upstanding on each side of the flat portion 12, having holes therein into which outstanding lugs 15 on the member 3 extend to form a balanced pivot. It will be noted that the edge 16 of the hole 13 is so positioned 30 that rotational movement of the member 3 about the fulcrum 4 is limited, whereby puncturing of the side of the can by the point 2 is obviated.

In the embodiment shown in Figure 1, the fulcrum 4 lies outwardly (radially of the can) from 35 the point of engagement of the tooth 7. In this arrangement, the reaction of the lugs 15 at the fulcrum 4 tends to pivot the bracket about the point of engagement of the tooth 7 with a flange 8 thus initially pressing the foot 10 into engagement with the top of the can. An equilibrium of forces having been thus established, the fulcrum 4 becomes fixed with respect to the can and further effort applied to the handle 5 to rotate the point 2 about the fulcrum 4 causes perforation 40 of the can, as foot 10 assists tooth 7 in taking the reaction, and a shearing action toward the wall of the can. The sides of the member 3 from the point 2 backwardly constitute shearing surfaces, and the fixing of the pivot point as aforesaid by 45 the establishment of an equilibrium of forces, results, upon rotation of the member 3 into the can, in a cutting action on each side of the member 3. Due to the shape of the member 3, the cut material is rolled. It will be noted that the cut- 50 55

ting action has not reached its maximum in the illustration. The member 3 has not yet contacted with the wall 16 of the hole 13.

Referring to Figure 2, there is shown a can 5 punch comprising a point 2' formed at the end of a member 3', the extension of which forms a handle 5'. The member 3' has an opening therein through which extends a bracket 3' which is provided with a tooth 7' for engagement with the flange 8' of a can 9', and a foot 10'. The bracket 6' has a fulcrum 4' for engagement with the member 3'. The initial position of the can punch prior to perforation of the can is shown in dotted lines. The position of the can punch just 10 prior to its maximum movement is shown in solid lines. A shoulder 16' limits the rotational movement of the member 3' about the fulcrum 4' whereby puncturing of the side of the can is obviated.

20 In the embodiment shown in Figure 2, the foot 10' does not initially engage the top of the can to be punctured. The tooth 7' is engaged with the flange 8' of the can 9' and the point 2' is engaged with the surface to be punctured. Upward movement of the handle 5' first pivots the bracket 6' about the tooth 7' until the fulcrum 4' has reached a point where the line between the fulcrum 4' and tooth 7' is generally normal to the line joining the fulcrum 4' and the point 2'. The bracket 6' may move slightly in the slot in the member 3' until the fulcrum 4' has found the place where an equilibrium of forces is established, whereupon the assembly rotates as a unit about the point of engagement of the tooth 7' and the flange 8'. 30

35 and the flange 8' until the foot 10' has engaged the surface to be punctured. When this condition is established, the point 2' may or may have not punctured the can, depending upon how far the top of the can is elevated above the point of engagement of the tooth 7' and the flange 8'. 40

40 When the foot 10' has engaged the surface to be punctured, however, the fulcrum 4' becomes fixed with respect to the can and the member 3' rotates about it, whereby the sides of the member 3' forcibly shear the punctured can toward the wall of the container. The sides of the member 3' are shear surfaces adapted for cutting the metal, being preferably squarely formed and smooth. The shape of the member 3' is such that the sheared metal is not rolled but is forced backwardly as a flap to lie flat against the side of the can when the shoulder 16' has been engaged and the movement has reached its limit. A tongue 17 is struck outwardly from the bracket to avoid the bracket slipping out of the hole in the member 3' when the implement is removed from the can.

55 In Figure 3 there is shown a simpler form of can punch generally similar to the form shown in Figure 1. In this embodiment a point 2'' and a member 3'' are mounted for rotation about a fulcrum 4'' by means of a handle 5''. The fulcrum 4'' is supported by a bracket 6'' having a tooth 7'' and a foot 10''. In this particular embodiment the bracket is a flat stamping riveted to the member 3'', the rivet constituting a pivot point at the fulcrum 4''. The member 3'' and handle 5'' are portions of the same stamping, the end of the member 3'' being turned to approximately ninety degrees from the plane of that portion which lies adjacent the bracket, thereby forming a shear member and puncture point. The shear member is preferably generally triangular in shape expanding in section rearwardly of the point 2'', whereby the hole sheared in the can

has its greatest width nearest the edge of the can. In this respect, the punch shown in Figure 3 is the same as the punches shown in Figures 1 and 2.

5 The side of the member 3'' as indicated at 18 serves to limit the rotation of the member 3'' about the fulcrum 4'' by engaging the bracket 6''.

10 It will be observed that my improved punch is not limited in any respect by the diameter of the can being operated upon, and that no clamps are required to hold the can, the implement being operable with one hand by a simple upward movement. The arrangement of the parts as illustrated and described results in a very powerful gripping action on the can, and even prior to 15 the time the puncture point 2 has actually perforated at the top of the can, it is practically impossible to pull the device away from the can as long as upward pressure is applied in sufficient amount to keep the tooth of the bracket engaged 20 with the flange of the can. It is this powerful gripping action developed by the implement which renders it suitable for cans having flanges virtually no thicker than the material of the can. This condition exists in practically all soldered cans, which have no rolled bead at the edges. 25 The implement, of course, operates with equal facility on cans having rubber sealed rolled edges, or any other form of offset adjacent the top edge, and by the term flange as used in the claims with 30 reference to cans, I mean to include offset portions serving the function of the flange in the illustrated application of my can punch.

35 My improved can punch is economical to manufacture, the parts being easily formed by stamping. The embodiment shown in Figure 2 for example requires merely two stampings simple in contour and easily formed with a single operation. The assembly of this embodiment involves nothing more than slipping the bracket 6' in the hole in the member 3' and bending the tongue 17 sideways slightly to obviate the bracket slipping out of the hole. The embodiment shown in Figure 3 is slightly more difficult to form and in its assembly involves riveting, nevertheless it is not expensive to manufacture. The embodiment shown in Figure 1 involves a somewhat more complicated stamping. It is, however, no more involved than the forms commonly found in less efficient devices, it being borne in mind that my improved 40 can punch is a complete unit in itself requiring no extraneous bands or clamps, and that it will function efficiently upon cans of any size and flanges of practically any thickness, always placing the opening in the most efficient place for 45 emptying the can.

50 The associated elements of my improved can punch are so disposed that the reactions developed by thrusting the puncture point into the can and shearing the metal away from the punctured hole are most efficiently utilized for developing a gripping action to hold the implement to the can during the puncturing operation. In the embodiment shown in Figure 1, the foot of the bracket initially engages the surface to be punctured, causing the fulcrum point to be fixed 55 relative to the can even prior to the breaking through of the puncture point. Thus, the shearing motion is developed and made available immediately that the can has been pierced. In the embodiment shown in Figure 2, the pressure foot ordinarily engages the surface to be punctured after the puncture point has pierced the can so that the shearing action may or may not exist immediately after the can is pierced depending 70 75

upon whether the foot has or has not contacted with the surface being punctured. The pivot point in all cases is preferably so disposed with respect to the tooth, and the puncture point and 5 shearing surfaces adjacent it are so shaped, that as the puncturing member fulcrums on the pivot point increasingly wider portions of the puncturing member engage the surface being punctured whereby the opening formed is of greatest dimension adjacent the rim of the can. For thin 10 liquids this is not essential, but for more viscous fluids such as condensed milk it is desirable.

To my knowledge, my improved can punch is the first to utilize the reaction forces developed by 15 the mere raising of a handle to cause the punch to grip the upper flange of the can, thus freeing the operator from the annoyance of learning unfamiliar motions to operate the punch and also making the punch equally efficient for cans of 20 any height, diameter or character of flange.

While I have illustrated and described certain preferred embodiments of my invention, it will be understood that the invention is not so limited but may be otherwise embodied within the scope 25 of the following claims.

I claim:

1. A can punch comprising a rotatable member having a puncture point at the end thereof, and a bracket having a fulcrum thereon for the rotatable member, the bracket having a tooth for engaging the flange of a can to be punctured, the puncture point lying in advance of the tooth and fulcrum and the distance from the fulcrum to the tooth being great enough that the fulcrum will 30 lie above the top of the flange of a can to be punctured when the tooth has engaged the flange, and the bracket being freely pivoted at the fulcrum so that the parts will assume such position upon application to a can, and thus the reaction 35 of the member on the fulcrum acts to draw the tooth into engagement with the flange of a can being punctured.

2. A can punch comprising a rotatable member having a shear surface thereon terminating in a 40 puncture point at the end thereof, and a bracket having a fulcrum thereon for the rotatable member, the bracket having a tooth for engaging the flange of a can to be punctured, the puncture point lying in advance of the tooth and fulcrum 45 and the distance from the fulcrum to the tooth being great enough that the fulcrum will lie above the top of the flange of a can to be punctured when the tooth has engaged the flange, and the bracket being freely pivoted at the fulcrum so 50 that the parts will assume such position upon application to a can, and thus the reaction of the member on the fulcrum acts to draw the tooth into engagement with the flange of a can being punctured.

3. A can punch comprising a rotatable member having a puncture point at the end thereof, and a bracket having a fulcrum thereon for the rotatable member, there being a handle on the rotatable member disposed on the side of the fulcrum opposite the puncture point, the bracket having a fulcrum thereon for the rotatable member, the bracket having a tooth for engaging the flange of a can to be punctured, the puncture point lying in advance of the tooth and fulcrum 55 and the distance from the fulcrum to the tooth being great enough that the fulcrum will lie above the top of the flange of a can to be punctured when the tooth has engaged the flange, and the bracket being freely pivoted at the fulcrum so 60 that the parts will assume such position upon ap-

plication to a can, and thus the reaction of the member on the fulcrum upon rotational motion being imparted to the handle acts to draw the tooth into engagement with the flange of a can being punctured.

4. A can punch comprising a rotatable member having a shear surface thereon terminating in a puncture point at the end thereof, and a bracket for temporarily providing a fulcrum for the rotatable member while puncturing a can, said bracket 10 having a fulcrum for said rotatable member, a tooth for engaging the flange of a can to be perforated, and a foot for engaging the surface to be perforated, the foot lying in advance of the puncture point, and the tooth lying behind the puncture point whereby a reaction from the puncture point tending to draw the tooth into engagement with the flange of a can to be punctured operates to press the foot into engagement with the surface being punctured and thereby fixes the 15 pivot point with respect to the can, thus enabling the shear surface to sweep toward the tooth and shear the can from the point of initial puncture toward the flange.

5. A can punch according to claim 4 having 20 means on the bracket limiting the rotation of the rotatable member about the fulcrum.

6. A punch for flanged cans comprising a rotatable member and a bracket, said bracket including a pressure foot and a flange engaging 30 tooth, said rotatable member including a piercing point at one end thereof extending into shearing surfaces, said rotatable member being fulcrumed on said bracket, the fulcrum point being fixed when said foot and said tooth are in engagement 35 with a can, whereby shearing is effected upon rotation of the rotatable member.

7. A can punch comprising a member having a shearing surface terminating in a puncture point at the end of the member, and a bracket adapted 40 to engage a can during a puncturing operation and provide a temporary fulcrum for said member adjacent the end of the can, said bracket having a fulcrum for the member, a foot engageable with the surface to be punctured and a tooth engageable 45 with the flange of a can being punctured, the arrangement being such that the reaction on the fulcrum by the member during rotation thereof draws the tooth into engagement with the flange of the can being punctured and tends to rotate 50 the bracket about the tooth to press the foot into contact with the surface of the can, thus holding the bracket to the can solely by the reaction of the puncturing operation and fixing the fulcrum with respect to the can whereby shearing of the 55 can toward the tooth is effected upon rotation of the member.

8. A can punch comprising a generally flat stamping having a puncture point at one end thereof and a portion serving as a handle at the other end thereof, and a bracket retained in a hole in said stamping disposed adjacent the puncture point, the bracket being retained by a protuberance engageable with the upper side of the stamping to form a fulcrum therefor, and by a distortion of the surface of the bracket below the stamping, said bracket terminating at one end in a tooth engageable with the flange of a can to be punctured, and having a foot at the other end thereof engageable with the can surface to be 70 punctured.

9. A can punch comprising a generally flat stamping having a puncture point at one end thereof and a portion serving as a handle at the other end thereof, and a bracket retained in a hole 75

in said stamping disposed adjacent the puncture point, the bracket being retained by a protuberance engageable with the upper side of the stamping to form a fulcrum therefor, and by a distortion 5 of the surface of the bracket below the stamping, said bracket terminating at one end in a tooth engageable with the flange of a can to be punctured, and having a foot at the other end thereof engageable with the can surface to be punctured, 10 and means on the bracket limiting the rotation of the member upon the fulcrum.

10. A can punch comprising a rotatable member having a puncture point at the end thereof, and a bracket for engagement with a can to be punctured, a fulcrum on said bracket about which 15 said member is rotatable, a tooth at one end of said bracket and a foot at the other end thereof, the foot and tooth being so disposed with respect to the fulcrum that the reaction of the member 20 on the fulcrum tends to rotate the bracket about

the tooth in the same direction of rotation as the rotation of the rotatable member inducing the reaction.

11. A can punch comprising a rotatable member having a generally claw-shaped puncture point with shear surfaces on the sides thereof, and a bracket pivoted to said member, a tooth on the bracket disposed a smaller distance from the pivot than from the puncture point and lying in a plane generally normal to the plane through the pivot 10 including the puncture point upon initial application of the can punch to a can to be punctured, whereby the forces induced by rotation of the puncture point forces the tooth into engagement with a flange on the can, the claw-shaped puncture point tending to draw the tooth radially into closer engagement with the can during continued 15 enlargement of a perforation.

BERNARD E. DOUGHERTY. 20
